UNITED STATES PATENT OFFICE.

MONTRAVILLE M. WOOD, OF BERWYN, ILLINOIS.

STRING MESSAGE-HOLDER FOR WIRELESS OR OTHER TELEGRAPH MECHANISM.

1,346,476.

Specification of Letters Patent. Patented July 13, 1920.

Application filed April 4, 1919. Serial No. 287,547.

To all whom it may concern:

Be it known that I, MONTRAVILLE M. Wood, a citizen of the United States, residing at Berwyn, in the county of Cook and State of Illinois, have invented a certain new and useful Improvement in String Message-Holders for Wireless or other Telegraph Mechanism, of which the following is a specification.

10 There are on the market a variety of wireless telegraph and ordinary telegraph mechanisms operated by moving a mechanical member having thereon signal making devices corresponding in arrangement to the 15 letters of the alphabet or other signals which are to be produced.

The object of this invention is to provide a novel form of message holder to be passed adjacent to a machine of this class to operate 20 the sending switch. The invention consists in means for carrying out this object, which can be easily and cheaply made, which is satisfactory in operation and is not readily liable to get out of order. More particularly, the invention consists in taking an 25 ordinary string or cord, placing along its length enlargements arranged in accordance with the signals to be made or sent, said enlargements being adapted to operate the 30 sending switch of the telegraph apparatus. In cases where the switch closes a circuit which does not include the message carrier, these enlargements are most easily and 35 cheaply made by tying ordinary knots in the string. In cases where the switch is of such a character that the circuit is completed through the message holder, the enlargements are made of a current carrying 40 substance, as for instance a lump of plum-bago pasted on the string. The invention further consists in the features and details 45 of construction hereafter more fully set forth in the specification and claims.

Referring to the drawings, in which similar numerals indicate the same parts throughout the several views,

Figure 1 illustrates a double ended string and

Fig. 2 a continuous string each adapted, 50 when carried by proper mechanism, to pass through or adjacent to the telegraph apparatus sending switch.

Fig. 3 is a diagrammatic view of a telegraph mechanism and its switch operated by 55 the message holder of this invention, the switch being of such a character that closure

of the switch does not send current through the message holder.

Fig. 4 is a diagrammatic view of a telegraph mechanism in which the sending 60 switch is of such a character that its closing requires the passage of current through or over a portion of the message holder.

Fig. 5 is a sectional view through the enlarged member of the message holder of 65 Fig. 4.

As telegraph mechanism of the class described is well known in the art, no attempt is made in the drawing to show the entire machine or the mechanism for holding and moving the message holder through 70 the machine.

Fig. 3 shows diagrammatically in its upper portion, a telegraph system 10, energized by current in an electric circuit 12, which is 75 completed when the flexible switch member 14, attached to a stationary support or block 16 at 18 is moved upward into engagement with contact point 20. In this type of device the current in the circuit 12 passes directly 80 from member 14 to contact point 20 and does not have to pass through the message holder which passes between switch member 14 and block 16 to move member 14 into engagement with switch point 20. In this type of device 85 the message holder consists in a plain string or cord 22 having ordinary knots 24 tied at suitable intervals along its length in accordance with the spacings of the Morse alphabet or other signal system which is to 90 be used, as is suggested in the more or less complete message holder shown in Figs. 1 and 2.

In the operation of the device, the machinery (not shown) moves cord 22 through 95 the switch mechanism and every time a knot 24 passes under switch member 14, it flexes that member up into engagement with contact point 20, thus completing the circuit and sending an electric signal through the 100 telegraph mechanism. As soon as the machine carries the knot 24 out from between members 14 and 16, switch member 14 springs back to normal position, as shown, 105 thus breaking the circuit and leaving the device ready to receive the signal produced when the next knot 24 passes through the switch. This is the simplest and cheapest form of message holder of this invention.

In the device of Fig. 4, the diagrammatically shown telegraph mechanism 30 is operated by the closing of an electric circuit 110

32 whose switch consists of two switch members 34 and 36, separated by an insulator 38, these switch members being adapted for electrical connection, one to 5 the other, through an outside conductor member passed between them. In this type of device, string 40 is provided, as before, the switch closing members being made by applying along the string at proper intervals touches of mucilage 42 covered with plumbago 44 or some other metallic substance, such for instance as aluminum dust or gold dust which is capable of transmitting electric current around the string 40. 10 The string itself serves as an insulator between the successive enlargements 42-44, shown.

In principle there is no reason why knots cannot be tied in the string 40, as is in 20 string 22, and these knots covered with plumbago or other conducting material, but in actual practice, the construction shown in Fig. 5 has proved satisfactory.

In the operation of this type of telegraph 25 mechanism, the machinery feeds string 40 along, as before, and every time a plumbago covered member 44 passes between the switch members 34 and 36, it completes the circuit 32 and operates mechanism 30. 30 This operation ceasing as soon as member 44 passes out from between the switch members 34 and 36. The apparatus then automatically restores itself to normal position, ready for the passage of the next member 44.

The message holder has been described as used solely in the sending of messages, but obviously if a machine, forming no 40 part of this present invention, exists or is hereafter invented which will cause the receiving end of a telegraph system to place enlargements 44 on the string 40, passed

through the receiving mechanism as messages are coming in, there is no reason why the resulting message holder cannot be used 45 to read the message from.

The word "cord" is defined in the Standard dictionary "a string or small rope made by twisting several strands together; twine." It is in this sense that the word 50 "cord" is used in the claims.

Having thus described my invention, what I claim as new and desire to secure by Letters Patent, is:—

1. In a telegraph apparatus, in combination with a signal switch mechanism; a cord, adapted for movement with reference to said switch, having knots tied along its length to act as switch operating members, said knots arranged at predetermined 60 points along the cord in accordance with the signals to be sent.

2. In a telegraph apparatus, the combination with a signal switch mechanism, a cord adapted for movement with reference to 65 the switch, said cord having knots tied along its length and conductive material covering each knot so as to make it a conductive enlargement adapted to complete the switch circuit, said enlargements being 70 arranged at predetermined points in accordance with the signals to be sent.

3. As a signal switch operator, a cord having knots tied along its length at intervals arranged in accordance with the signals to be given. 75

In witness whereof, I have hereunto subscribed my name in the presence of two witnesses.

MONTRAVILLE M. WOOD.
